UNITED STATES PATENT OFFICE

2,330,316

HEEL-ATTACHING MACHINE

John F. Standish, Winthrop, Mass., assignor to
United Shoe Machinery Corporation, Flemington, N. J., a corporation of New Jersey

Application April 16, 1942; Serial No. 439,201

13 Claims. (Cl. 1—32)

This invention relates to heel-attaching machines equipped to operate upon shoes which are without counters and quarter portions and are commonly known as mules.

It is an object of the present invention to equip the heel-attaching machine disclosed in United States Letters Patent No. 2,178,615, granted November 7, 1939, on an application filed in the names of John F. Standish and Lester S. Macdonald, for operating upon mule work.

The illustrative machine is provided with gages for locating the heel end of the sole of the mule and the heel which is to be attached to the mule in predetermined positions upon the jack of the machine. The gages normally lie in the path of movement of the loader block of the machine and are slidably lowered as a unit in response to movement of the loader block so that fastenings carried by the block may, without interference, be delivered to the jack. In order to change the relation of the work to points of insertion of the fastenings into the work, the sole and heel gages are adjustable as a unit heightwise and lengthwise of a shoe mounted upon the jack, the heel gages being individually adjustable with relation to the sole gages in converging paths toward and away from the central portion of the work-supporting face of the jack.

Preparatory to operating upon regular work, in which the rear end of a top plate of the jack is engaged by a shoe counter to position the shoe upon the jack, it is desirable to remove the above-mentioned gages to idle positions away from the jack. Accordingly, the gages of the illustrative machine, after being unlatched from their operative positions just rearward of the jack, may be swung laterally as a unit to idle positions at one side of the jack and may be latched in such positions.

Although the above work-positioning mechanism is described as embodied in the above-mentioned Letters Patent No. 2,178,615, it will be understood that such mechanism may be used advantageously in other heel-attaching machines.

The various features of the invention will be understood and appreciated from the following detailed description read in connection with the accompanying drawings, in which

Figs. 1 and 2 are side and front views, respectively, partly broken away and partly in section, of portions of the illustrative heel-attaching machine equipped for operating upon mule work;

Fig. 3 is a plan view of the machine on line III—III of Fig. 1, the heel holdown and other

parts of the machine having been omitted; and Fig. 4 is a section on line IV—IV of Fig. 3.

The illustrative machine is described with reference to the attachment of a heel 20 to a shoe 5 or mule 22 (Fig. 1) and includes gages 24, 26 for positioning, respectively, the heel end of a sole 28 of the mule and the heel 20 which is to be received by the mule, with reference to a top plate 30 of a jack or work support 32, and a carrier 34 for the gages. The machine, with the exception of mechanism for supporting and operating the gages 24, 26, as will appear later, may be identical with the heel-attaching machine disclosed in the above-mentioned Patent No. 2,178,615. The illustrative work-positioning mechanism is similar in many respects to corresponding mechanism which is disclosed in United States Letters Patent No. 2,059,331, granted November 3, 1936, on an application filed in the name of George W. Freeman, and which, because of limitations of space and other considerations, cannot be used advantageously in connection with the improved heel-attaching machine disclosed in Patent No. 2,178,615.

The jack 32 comprises a steel forging 36 (Figs. 1 and 2) into which are threaded a plurality of driver tubes 38 (Fig. 1) constructed and arranged to receive drivers 40. When the machine is operating on regular work, the shoe is positioned upon the jack 32 by contact of the inside counter portion of the shoe with the top plate 30 of the jack. It will be appreciated that, since mules 22 have no counters, it is desirable to provide the gages 24, 26 for positioning such work in the machine.

Mounted upon the frame 42 (Figs. 1 and 2) of the heeler is a casing 44 for supporting mechanism which guides a nail loader block 46 from its nail-receiving position, shown in Fig. 1, to a nail delivering position above the jack and back to its receiving position. Nails 48 (Fig. 1) drop with their heads upward through nail tubes 50 and, after passing through registering openings 47 in a foot plate 49, drop into pockets 51 of the loader block, a shutter 52 slidably mounted on the block at this time having its openings 53 registering with the openings 47 in the foot plate and the pockets 51 of the block. As the nail loader block 46 is reciprocated, together with a slide 55 (Fig. 3) lengthwise of guideways 54 (Fig. 1) formed in the casing 44, it is rotated with reference to the slide upon trunnions 56, with the result that the block at the forward end of its stroke is positioned upside down above the top plate 30 of the jack 32, its openings 53 register-

ing with openings 58 (Fig. 1) in the driver tubes 38. Just before the loader block 46 arrives at the forward end of its stroke, the shutter 52 is slid with reference to the block by the engagement of a screw 60, which is carried by the shutter, with the top plate 30, thereby enabling the nails to drop, heads downward, into the tubes 38 of the jack.

After positioning the rear end of the sole 28 upon the top plate 30 and the heel 20 upon the sole by the use of the gages 24, 26, a pressure head 62, which is mounted upon vertical guides 64 of the main frame, is lowered, thereby causing tread and rear abutments 66, 68, constituting the heel holdown, to engage the top lift and rear faces, respectively, of the heel to force it against the sole supported by and positioned upon the top plate. Since the machine, with the exception of the gages 24, 26 and the mechanism for supporting them and for actuating and retaining them inactive, is identical with the machine disclosed in Patent No. 2,178,615, no further description herein of the machine is deemed to be necessary.

Secured by a screw 70 and a dowel pin 71 to the left vertical guide 64 is a bracket 72 a depending portion of which has alined bores 74 (Fig. 2). Mounted for sliding movement in the bores 74 is a vertical pin 76 having secured to it by a dowel pin 78 the carrier 34 which, together with the pin 76, is constantly urged upward by a spring 80, upward movement of the pin and the carrier being limited by the engagement of the carrier with the bracket 72, which serves as a stop. When the machine is operating upon mule work, the carrier 34 is held against swinging movement about an axis 82 (Fig. 2) of the vertical pin 76 by a latch pin 84 which is secured to the carrier and fits in a bore 86 of the bracket 72.

The carrier 34 includes a terminal portion 88 which is provided with a tongue 87 (Fig. 3) which fits in a vertical groove 89 of a guide portion 90 of the carrier and is adjustable along the groove through the provision of a slot-and-screw connection 92. The sole gage 24 is provided with a groove 91 (Figs. 2 and 3) registering with a horizontal tongue 93 (Fig. 2) formed in the intermediate portion 88 of the carrier, the gage being adjustable in directions 94 extending forwardly and rearwardly of the machine with reference to the terminal portion 88 of the carrier through the provision of a slot-and-screw connection 96 (Fig. 3).

The sole gage 24, which may be referred to as a fork, has work-engaging faces 98 (Figs. 2 and 4) and is preferably made in one piece and has its central axis 100 (Fig. 3) in alinement with the heightwise median plane of the top plate 30 of the jack. The heel gages 26 have upstanding work-engaging flanges 102 (Figs. 3 and 4), which are engaged by the rim of the attaching face of the heel 20, and shanks which fit in guideways 104 (Fig. 3) formed in the sole gage. The gages 26 may be secured in different adjusted positions in the guideways 104 through the provision of screws 106 which are threaded into the sole gage and pass through elongated slots 108 (Fig. 4) in the shanks of the heel gages. The heel gages 26, accordingly, may be described as being adjustable with relation to the sole fork or gage 24 toward and away from the central portion of the work-receiving face of the top plate 30 of the jack 32.

It will be appreciated that when the gages 24, 26 are in their raised operative positions, shown in Fig. 1, they lie in the path in which the loader

block 46 travels during its nail delivering operation. Consequently, during the operation of the machine it is desirable temporarily to move the gages out of said path and, with this in view, the gage carrier 34 has secured to it by screws 110 a bar or cam 112 having an upper cam surface 114 which, during the forward movement of the loader block 46, is engaged by a cam roll 116 mounted upon the loader block slide 55. The carrier 34 is therefore depressed, together with the vertical pin 76, against the action of the spring 80, it being prevented from turning about the axis 82 of the pin during such movement by the engagement of the latch pin 84 in the bore 86 of the bracket 72.

Preparatory to operating upon shoes having counters (not shown), it is desirable to move the gages 24, 26 to idle positions away from the top plate 30, since the top plate itself, by reason of its engagement with the inside of the counter portion of the shoe, is used to position the work in the machine. Accordingly, the carrier 34, when in its operative position shown in Figs. 1, 2 and 3, may be depressed against the action of the spring 80 and swung outwardly, that is, rearwardly and to the left, as viewed in Fig. 2, about the axis 82 of the pin 76 until the latch pin 84 lies beneath a bore 118 in the bracket 72. Downward pressure against the carrier 34 is then released to permit the carrier to be raised by the spring 80, the pin 84 entering the bore and positively holding the carrier, together with the cam 112 and the gages 24, 26, in its idle position away from the operative parts of the machine.

Although the invention has been described with reference to mules, it will be understood that the above-disclosed work-positioning mechanism may be used effectively in connection with the attachment of heels to open-back sandals.

Having described my invention, what I claim as new and desire to secure by Letters Patent of the United States is:

1. In a heel-attaching machine, a shoe support, transferring means movable to deliver fastenings to the support, and a gage co-operating with the support, said gage being movable heightwise of a shoe upon the support in response to movement of said transferring means to displace said gage out of the path of movement of said means, said gage also being mounted for movement laterally of the shoe into an idle position out of the path of movement of said transferring means.

2. In a heel-attaching machine, a jack, a nail loader movable to deliver nails to the jack, a frame, a pin journaled in the frame and extending heightwise of the jack, a stop, a carrier mounted on the pin, a work-positioning gage mounted upon the carrier, means for restraining the carrier from movement about the axis of the pin, a spring for urging the carrier heightwise of the jack to a predetermined position determined by the stop, and means movable in response to movement of the nail loader for moving the gage temporarily from an active position in which it co-operates with the jack.

3. In a heel-attaching machine, a jack, a nail loader movable to deliver nails to the jack, a frame, a pin which is journaled in the frame and has its axis extending heightwise of the jack, a stop, a carrier secured to the pin, a work-positioning gage mounted upon the carrier, means for restraining the carrier from movement about the axis of the pin, a spring for raising the carrier heightwise of the jack to a predetermined position

determined by the stop, means movable in response to movement of the nail loader for moving the gage from a gaging position adjacent to the jack, and means for enabling the carrier to be released for rotation together with the pin about the axis of the pin in order to move the gage away from its active position in which it co-operates with the jack.

4. In a heel-attaching machine, mechanism comprising a jack for supporting a shoe and a heel clamped to the shoe, a loader block movable in a predetermined path toward and away from the jack, gages, resilient means for constantly urging the gages into active co-operative positions with relation to the jack, in which positions they are arranged in the path of movement of the loader block and are engaged respectively by the rear end of the sole of the shoe and by said heel, means movable in response to movement of the loader block for moving the gages heightwise of the jack to positions out of the path of movement of said block, and means for swinging the gages to one side of the path of movement of the block to idle positions in which they are unaffected by movement of the block.

5. In a heel-attaching machine, a jack, a pin, a fixed frame, said pin being mounted in said frame for movement heightwise of the jack and for rotation about its axis, a carrier secured to the pin, gages mounted upon the carrier, a nail loader movable to deliver nails to the jack, means movable with the nail loader for actuating the carrier heightwise of the jack, thereby causing the gages to be moved temporarily from active positions in the path of movement of the nail loader to positions out of said path, means for enabling the carrier together with the gages to be moved from their active positions into idle positions located away from and to one side of said path, and means for retaining the carrier in its active and idle positions respectively.

6. In a heel-attaching machine, a frame, a jack, a carrier movable heightwise of the jack, pairs of gages supported by the carrier, said pairs of gages being adjustable as a unit upon the carrier heightwise and lengthwise of a shoe positioned on the jack and one pair of gages being individually adjustable with reference to the other pair of gages, a nail loader movable in a predetermined path, a spring operating yieldingly against the carrier for supporting the gages in active co-operative positions adjacent to the jack in which positions the gages are arranged in the path of movement of the loader, means associated with the nail loader for actuating the carrier to move the gages out of said path, said carrier being mounted for swinging movement about an axis extending heightwise of the jack to enable the carrier to be moved to an idle position in which it will not be contacted by the nail loader, and means for retaining the carrier in its active and idle positions respectively.

7. In a heel-attaching machine, a jack, a nail loader movable to deliver fastenings to the jack, a gage for positioning a mule, a gage for positioning a heel which is to be attached to the mule, a carrier for the gages, means comprising a spring for normally retaining the carrier in a

position in which the gages are in active gaging positions adjacent to the jack and are located in the path of movement of the loader, means responsive to movement of the nail loader for moving the gages out of the path of movement of the loader into inactive positions, means for causing the gages to be moved from their inactive positions back to their gaging positions adjacent to the jack, said carrier being movable to an idle position at one side of the jack to adapt the machine for regular work, and means for locking the carrier in a position in which the gages are in active and idle positions respectively.

8. In a heel-attaching machine, a frame, a jack mounted upon the frame and having a work-supporting face, a carrier movable with relation to the frame, a sole fork mounted upon the carrier, means for securing the sole fork upon the carrier in different adjusted positions lengthwise and heightwise of the jack, and heel gages mounted upon the sole fork, said gages being adjustable with relation to the sole fork in converging paths toward and away from the central portion of the work-supporting face of the jack.

9. In a heel-attaching machine, a frame, a jack which is mounted upon the frame, gages for positioning a mule on the jack and a heel on the mule, a hold-down for forcing the positioned heel against the mule, an overhanging guide for said hold-down, and means secured to the guide and constructed and arranged to support the gages in their operative positions adjacent to the jack and also to permit the gages to be swung to idle positions at one side of the jack.

10. In a heel-attaching machine, a jack, a gage arranged for contact with a shoe upon the jack, a pair of gages arranged for contact with opposite sides of the rear of a heel upon the sole of the shoe, and means arranged to fix the heel gages individually in different positions with relation to the shoe gage.

11. In a heel-attaching machine, a jack, a unitary gage arranged for contact with a sole of a shoe upon the jack, a pair of gages which are arranged for contact with a heel upon the shoe and which are individually adjustable in converging paths, and means arranged to fix the heel gages individually in their adjusted positions.

12. In a heel-attaching machine, a frame, a shoe support mounted upon the frame, a slide guided for vertical movement upon the frame, a spring upon which the slide rests, a transferring member movable to deliver fastenings to the support, and means acting in the movement of the transferring member for reciprocating the slide along the guides and compressing the spring.

13. In a heel-attaching machine, a frame, a shoe support mounted upon the frame, a transferring member movable to deliver fastenings to the support, a gage for engaging the rear end of the sole of a mule to position the same upon the jack, a gage for positioning a heel upon the mule, a slide for carrying the gages, said slide being guided for vertical movement upon the frame, and means movable in response to movement of the transferring member for reciprocating the slide along the guide.

JOHN F. STANDISH.
